UNITED STATES PATENT OFFICE

152,210

DESIGN FOR A DISPENSER CABINET FOR PAPER CUPS OR THE LIKE

Albert A. Perelman, Brooklyn, N. Y., assignor to
Lily-Tulip Cup Corporation, New York, N. Y.,
a corporation of Delaware

Application December 27, 1946, Serial No. 135,807

Term of patent 14 years

(Cl. D52—2)

To all whom it may concern:

Be it known that I, Albert A. Perelman, a citizen of the United States and a resident of Brooklyn, in the county of Kings and State of New York, have invented a new, original, and ornamental Design for a Dispenser Cabinet for Paper Cups or the like, of which the following is a specification, reference being had to the accompanying drawing, forming part thereof, wherein:

Fig. 1 is a perspective view of a dispenser cabinet for paper cups or the like, embodying my new design;

Fig. 2 is a side elevational view of the device shown in Fig. 1; and

Fig. 3 is a top plan view of the device shown in Fig. 1.

I claim:

The ornamental design for a dispenser cabinet for paper cups or the like, substantially as shown.

ALBERT A. PERELMAN.
